UNITED STATES PATENT OFFICE.

DANIEL McLANE STOREY, OF WEEPING WATER, NEBRASKA.

CONCENTRATOR.

SPECIFICATION forming part of Letters Patent No. 749,706, dated January 12, 1904.

Application filed August 8, 1902. Serial No. 118,931. (No model.)

To all whom it may concern:

Be it known that I, DANIEL McLANE STOREY, a citizen of the United States, and a resident of Weeping Water, in the county of Cass and State of Nebraska, have invented a new and Improved Concentrator, of which the following is a full, clear, and exact description.

The invention relates to concentrators such as shown and described in the application for Letters Patent of the United States, Serial No. 113,284, filed by me June 26, 1902.

The object of the present invention is to provide a new and improved concentrator which is simple and durable in construction and designed for treating materials from stamp-mills or from placers to effectively separate the precious metal from the tailings.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a plan view of the improvement. Fig. 2 is a longitudinal sectional elevation of the same on the line 2 2 of Fig. 1. Fig. 3 is a transverse section of the same on the line 3 3 of Fig. 2. Fig. 4 is an enlarged sectional side elevation of the adjustable connection for varying the stroke of the concentrating-box, and Fig. 5 is a sectional plan view of the same.

The ore-concentrator is mounted on a suitably-constructed base or frame A, on the side of which are pivoted upwardly-extending arms B, supporting a concentrating-box C, connected at its forward end by a link D with a slide D', held adjustable in a rock-arm D², provided with trunnions D³, journaled in suitable bearings carried on the frame A. A set-screw D⁴ serves to fasten the slide D' in place in the rock-arm D² after the desired adjustment is made—that is, after the desired throw is given to the concentrating-box C.

The rock-arm D² is provided on its upper end with lugs D⁵, pivotally connected by a pitman E with the crank-arm F' of a main shaft F, extending transversely and journaled

in suitable bearings on the main frame or base A. The main shaft F carries the usual fly-wheel F², connected by a belt with other suitable machinery for imparting a rotary motion to the shaft F, so that the latter by the crank F', pitman E, rock-arm D², and link D imparts a forward-and-backward rocking motion to the concentrating-box C, supported on the swinging arms B. Now by moving the slide D' farther up or farther down in the rock-arm D² more or less throw can be given to the concentrating-box C without varying the crank-arm F' of the main shaft F. It is understood that this adjustment is essential for treating materials of different specific gravity.

The concentrating-box C is provided at its forward end with a receiving-chute C', which delivers the material to be treated to a V-shaped riffle C², extending transversely in the box at the forward end thereof, and in the box are arranged other riffles C³, C⁴, and C⁵, located one alongside the other and similar to the riffle C², adjacent to the riffle C². The rearmost riffle C⁵ discharges into a chute C for carrying off the tailings. The first two riffles C² and C³ are provided with valved outlets G, and similar outlets G' lead from the bottoms of the riffles C⁴ C⁵. The valved outlets G and G' are connected by hose or pipes G² G³ with transverse conveyers H H', respectively, arranged on the base or frame A and discharging at opposite sides into elevators I I' for delivering the concentrates to chutes J J', discharging into settling-tanks K K', located on opposite sides of the machine, as plainly illustrated in the drawings. The settling-tanks K K' receive the water and concentrates from the riffles C² C³ and C⁴ C⁵ of the concentrating-box C by means of the connections above described. By having the connection between the riffles and elevators in the manner set forth it is evident that the water-level in the elevators corresponds with that in the riffles, and consequently a suction action on the part of the conveyers and elevators relative to the riffles does not take place, and consequently tailings are not drawn down in the riffles and passed to the settling-tanks. By the construction described it requires but little power to move the water and concen-

trates to the settling-tanks. I do not limit myself to the number of riffles in the concentrating-box, as more or less riffles may be employed, according to the nature of the material to be treated.

In dry placer-work or dry work of any kind the conveyers and elevators may be dispensed with, and the concentrates are then directly dropped into a box below the riffles.

- 10 In order to actuate the conveyers H and H', I provide an endless sprocket-chain L, passing over sprocket-wheels L' L², secured on the shafts of the conveyers H H', the said sprocket-chain also passing over a sprocket-wheel N, secured on a shaft N', journaled on the base A and carrying a sprocket-wheel N², connected by a sprocket-chain N³ with a sprocket-wheel N⁴ on the main shaft F. Thus when the latter is rotated the rotary motion is transmitted by the sprocket-wheels and chains described to the shafts of the conveyers H and H' to cause the latter to convey the concentrates sidewise to the elevators I and I'. The latter are also actuated from the chain 25 L, and for this purpose the latter passes over sprocket-wheels O O', secured on transverse shafts O² O³, journaled in suitable bearings in the base A, and the said shafts O² O³ are connected by gearings P P' (see Fig. 3) with the 30 shafts of the elevators I I'. Thus the traveling motion of the chain L causes rotation of the shafts O² O³, which by the gearings P P' actuates the elevators I I' to move the concentrates delivered by the conveyers H H' to 35 the chutes J J', which in turn discharge the concentrates into the settling-tanks K K'. The sprocket-chain L also passes over idlers Q Q', carried by the base A, to hold the sprocket-chain in proper position relative to the 40 sprocket-wheels L', O, and O'.

The operation is as follows: When the shaft F is rotated, a forward-and-backward swinging motion without undue jar is given to the concentrating-box C, and as the material is fed over the chute C' and passes into the riffle C² it is evident that the material is agitated by the forward-and-backward rocking motion, so that the heavier particles readily settle in the apex of the first riffle C². Lighter particles pass over the riffle C² to the next riffle C³, in which some of the heavier particles settle, while the lighter particles pass on to the next riffle C⁴, in which again some of the heavier particles settle and the lighter pass to the riffle C⁵, in which any remaining heavy particles settle, while the tailings finally pass over the chute C⁶ to the rear end of the machine. The concentrates settling in the several riffles C² C³ and C⁴ C⁵ can be discharged from time to 60 time by the operator opening the valves G and G', and the concentrates thus flowing from the riffles to the conveyers H H' are moved transversely by the latter and finally discharge into the elevators I and I', which elevate the concentrates to the chutes J and J',

which discharge the concentrates into the settling-tanks for further treatment.

From the foregoing it will be seen that the graduated concentrates are discharged into separate settling-tanks—that is, the concentrates from the riffles C² and C³ are discharged into the tank K, while the concentrates from the riffles C⁴ and C⁵ are discharged into the tank K'. 70

It is understood that owing to the forward-and-backward-rocking motion given to the box C in a longitudinal direction—that is, at right angles to the direction of the riffles—the material is sufficiently agitated to cause a proper separation between the heavier particles and the tailings, so that the heavier particles settle in the apex bottoms of the riffles, while the tailings move on and are finally discharged over the chute C⁶ to the outside of the machine. 75

Having thus described my invention, I claim as new and desire to secure by Letters Patent—

1. A concentrator, comprising a box having a rocking motion and provided with transversely-extended V-shaped riffles, means for operating the box, settling-tanks arranged at the sides of the box and adapted to be filled with water to the level of the water in the box, a conveyer for conveying the concentrates from the bottoms of the forward riffles to one 90 of the settling-tanks, a conveyer for conveying the concentrates from the bottoms of the rear riffles to the other settling-tank, and means for operating the conveyers from the box-operating means, as set forth. 95

2. A concentrator, comprising a pivotally-mounted box, riffles extending in the said box in a direction at right angles to the running motion of the box, the riffles being V-shaped, means for imparting a swinging movement to 100 said box, transverse conveyers arranged below the box, flexible connections between the conveyers and the apex bottoms of the riffles, elevators connected with the outer ends of 105 said conveyers, settling-tanks at opposite sides of the box and into which discharge the said elevators, and means for operating the conveyers and elevators from the box-operating means, as set forth. 110

3. A concentrator, comprising a box having 115 a rocking motion, riffles extending in the said box in a direction at right angles to the running motion of the box, the riffles being V-shaped, transverse conveyers arranged below the box, flexible connections between the conveyers and the apex bottoms of the riffles, elevators connected with the outer ends of 120 said conveyers, settling-tanks at opposite sides of the box and into which discharge the said elevators, a main shaft, and means for imparting 125 motion to the box, conveyers and elevators from the said main shaft, as set forth.

4. In a concentrator, the combination with a swinging concentrating-box provided with 130 riffles, and means for swinging said box, of

conveyers arranged below the bottom of the box and provided with sprocket-wheels on their shafts, flexible connections between the bottom of the box and the conveyers, an end-
5 less sprocket-chain passing over the sprocket-wheels of the conveyers, means for operating the sprocket-chain, elevators into which discharge the conveyers, and means for operating the elevators from the endless chain, as set
10 forth.

5. In a concentrator, the combination with a swinging concentrating-box provided with riffles, and means for swinging said box, of conveyers provided with sprocket-wheels on
15 their shafts, flexible connections between the box and conveyers, an endless sprocket-chain passing over the sprocket-wheels of the conveyers, means for operating the sprocket-chain from the box-operating means, elevators into
20 which the conveyers discharge, shafts provided with sprocket-wheels over which passes the sprocket-chain, elevators, and gearing between the elevator-shafts and the shafts carrying the sprocket-wheels, as set forth.

25 6. A concentrator, comprising a box mounted upon swinging supports and provided with V-shaped riffles extending transversely of the box, means for swinging said box, conveyers arranged transversely below the box, flexible
30 connections connecting each conveyer with the

apex bottoms of the riffles, one at the forward end of the box and the other at the rear end, elevators into which the conveyers discharge, a tank at each side of the box and into which the elevators discharge, and means for operating the conveyers and elevators from the box-operating means, as set forth. 35

7. A concentrator, comprising a box mounted on swinging supports, and provided with V-shaped riffles extending transversely of the box, means for swinging the box, said means including an adjusting device for regulating the throw of the box, conveyers arranged transversely below the box, flexible connections connecting each conveyer with the apex 40 bottoms of two of the riffles, elevators at the outer ends of the conveyers and into which said conveyers discharge, a settling-tank at each side of the box and into which the elevators discharge, and means for operating the 45 conveyers and elevators from the box-operating means, as set forth.

In testimony whereof I have signed my name to this specification in the presence of two subscribing witnesses.
